UNITED STATES PATENT OFFICE.

BERTRAM J. GOLDSMITH AND EMIL KOEB, OF NEW YORK, N. Y., ASSIGNEES TO PERFECT WINDOW REGULATOR CORPORATION, OF LONG ISLAND CITY, NEW YORK, A CORPORATION OF DELAWARE.

WINDOW AND OPERATING MEANS THEREFOR.

Application filed August 13, 1925. Serial No. 50,089.

This invention relates to windows and closures therefor and although it is not to be so limited it is particularly adapted in its application to windows of railroad cars, 5 busses and other vehicles.

The invention has for its principal object the production of a window employing a fixed screen at or adjacent the top or bottom of the window opening and a movable sash 10 which may be moved or slid adjacent the fixed screen to close the entire under opening.

A further object of the invention is the production of a window of the type specified in which the operating means for moving or actuating the sash shall be carried 15 by the fixed screen portion.

A further object of the invention is the production of a window of the above type 20 in which the operating means shall not only be carried by the fixed screen but shall be so positioned as to exert a pressure centrally of the sash thus obviating the possibility 25 of the sash jamming on either side thereof.

Other and further objects and advantages 30 of the invention will appear from the accompanying description taken with reference to the accompanying drawings showing a practical embodiment of the invention

and in which:

Fig. 1 is a front elevation of a window showing our invention applied thereto.

Fig. 2 is a horizontal section taken through the window.

Fig. 3 is a central vertical cross-section taken through the lower portion of the window.

Fig. 4 is a view similar to Fig. 1 but showing a modification.

Fig. 5 is a view similar to Fig. 2 of the modification.

Fig. 6 is a view similar to Fig. 3 of the modification.

Referring in detail to the several figures 45 of the drawings:

1 indicates the side members of a rectangular window frame while 2 is the upper member and 3 the lower member thereof which join the side members 1 together.

The frame may be that forming a side portion of the wall of a railroad car, a seat 4 for a passenger being shown in its proper position as respects the position of the window. The side members 1 are provided with suit-

able guide channels 5 in which the side rails 6 of a window sash 7 are slidable the lower rail of the sash being indicated at 8. The sash 7 may be raised upwardly from the position shown in Fig. 3 and into a suitable window well formed within the upper 60 member 2 but not shown.

At the lower portion of the window frame and occupying approximately half the space of the window opening is a fixed frame 9 the sides of which are secured to the side members 1 in any desirable manner forming no part of our invention. Said frame 9 is preferably provided with two somewhat enlarged rectangular openings containing 70 screens 10 as illustrated and is also provided, centrally thereof, with a rectangular or square housing 11 in which is mounted a worm or screw 12 supported by a bracket 13. Threaded on said worm or screw is a nut 14 conforming in shape to the shape of the housing. Carried by said nut 14 is a pin or other connecting member 15 fastened to a bracket 16 which is screwed or otherwise fastened to the lower rail 8 of the sash 7, said pin or connecting member extending 80 through a slot in the rear wall of the housing. Carried by the upper end of the worm or screw is a bevel gear 17 which meshes with a bevel gear 18 which is carried on the end of a shaft journalled in and extending 85 through the front wall of the housing 11. The outer wall of the shaft carries a rotatable crank or handle 19.

When it is desired to raise the sash 7 the crank or handle 19 is rotated motion being 90 translated through the bevels 18 and 17, through the worm or screw 12, through the pin 15 and nut 14 and to the sash. When the nut 14 strikes or abuts against the bracket 13 the sash has reached its limit of 95 upward movement as is obvious, the lower rail 8 thereof then being adjacent or in proximity to the top of the screen member 9. When the sash is so raised, ventilation 100 may be had through the screens 10 and said screens will prevent the thrusting of the passengers' heads or arms out of the window opening and will also prevent the throwing of articles through said openings. In inclement weather the sash may be lowered by rotation of the crank or handle 19 to effectively close the entire window opening. It will also be obvious, that inasmuch 105

as the thrust on the sash is a central one when the sash is actuated the tendency to bind of the side rails 6 in the channels 5 is obviated.

5 In the modification illustrated in Figs. 4, 5 and 6 the screen members are shown provided by a slot 20 centrally thereof having teeth on either side wall. A U-shaped bracket 21 extends through said slot and is 10 connected at its rear end by screws or other connecting means to the lower rail 8 of the sash. Extending through the arms of the bracket 21 is a pivot pin 22 to which is pivoted two handles 23 the inner ends or 15 shanks of which extend within the bracket and are normally spaced from each other by a compression spring 24 which is fastened to said inner ends. Said inner ends also each carries a locking lug 25 which interlock with the teeth on the side walls of the 20 slot 20 in an obvious manner.

To raise the sash in the modification the handles 23 are pressed together against the action of the spring 24 which releases the 25 lugs 25 from engagement with the teeth on the walls of the slot 20 whereupon the sash may be raised by pulling upwardly on the handles. The sash may be held in any adjusted position by merely releasing the handles whereupon the locking lugs 25 will automatically become engaged with the teeth on the side walls of the slot 20 by the action 30 of the spring 24 in an obvious manner.

We claim as our invention:

35 1. In a window, a frame providing a window opening, a fixed screen member adjacent one end of said opening, a movable sash in said opening adapted to close the same and means connecting said screen member 40 and sash for actuating said sash.

45 2. In a window, a frame providing a window opening, a fixed screen member adjacent one end of said opening, a movable sash in said opening adapted to close the same and movable away from and towards said screen member and means connecting said screen member and sash for actuating said sash.

50 3. In a window, a frame providing a window opening, a screen member fixed to said frame adjacent one end of said opening, a movable sash in said opening adapted to close

the same and means carried by said fixed screen member for actuating said sash.

4. In a window, a frame providing a window opening, a fixed screen member at one end of said opening and fixed to said frame, a movable sash in said opening adapted to close the same and to be brought into parallelism with said fixed screen member, means carried by said fixed screen member for actuating said sash and connected to said sash approximately centrally thereof. 55

5. In a window, a rectangular frame providing a window opening and having a window well in the upper portion thereof and provided with channels in the side members thereof, a screen member secured to said frame and closing a portion of said window opening, a sash slideable in said channels and 60 into said window well and actuating means mounted on said fixed screen member and connected to said sash. 65

6. In a window, a rectangular frame providing a window opening and having a window well in the upper wall thereof and channels in the side walls thereof, a window sash slideable in said channels and adapted to close said opening and also adapted to slide into said window well, a screen fixed to the lower 70 part of said frame and partially closing said opening and actuating means mounted on said screen and connected to said sash for actuating the same. 75

7. In a window, a frame providing a window opening, a sash slideable in said frame, a fixed screen member adjacent one end of said opening, a housing on said screen member having a slot in the rear wall thereof, actuating means within said housing and 80 connecting means extending through said slot and connected to said sash. 85

8. In a window, a frame provided with a window opening, a screen member in said opening, a sash member in said opening 95 adapted to close the same and means connecting said screen member and sash member for actuating one of said members.

Signed at New York, in the county of New York, and State of New York this 12th day 100 of August, A. D. 1925.

EMIL KOEB.
BERTRAM J. GOLDSMITH.
